UNITED STATES PATENT OFFICE.

JOHN DEEBLE, OF SOUTHBURY, CONNECTICUT, ASSIGNOR OF ONE-HALF
TO J. B. SAVAGE, OF SAME PLACE.

DESIGN FOR AN OX-SHOE.

SPECIFICATION forming part of Design No. 17,595, dated August 9, 1887.

Application filed May 11, 1887. Serial No. 237,899. Term of patent 7 years.

To all whom it may concern:

Be it known that I, JOHN DEEBLE, a citizen of the United States, residing at Southbury, in the county of Hartford and State of Connecticut, have invented and produced a new and original Design for Ox-Shoes, of which the following is a specification, reference being had to the accompanying drawing, forming part thereof.

10 The single figure of said drawing is a perspective view of my newly-designed ox-shoe, showing the bottom face and inner edge.

My shoe has the general form of an ordinary ox-shoe, including the ordinary calks, A B, at 15 the heel and toe ends, respectively.

I form upon the under face of the shoe an

ornamental shoulder or ledge, a, which extends along the junction of the body C of the shoe and its pad D, beginning near the heel-calk A and running forward to the end of the pad D, 20 where it merges into the inner edge of the body of the shoe, as shown.

I claim—

The design for an ox-shoe herein shown and described, the same consisting of the general 25 form of an ox-shoe and an ornamental shoulder or ledge extending along the junction of its body and pad.

JOHN DEEBLE.
